CONTINUOUS PROCESS FOR COUNTER CUR-
RENT CONTACTING OF TWO LIQUIDSRobert E. Wilson, Chicago, Ill., assignor to Stand-
ard Oil Company, Chicago, Ill., a corporation
of Indiana

Application December 18, 1931, Serial No. 581,927

10 Claims. (Cl. 196—13)

This invention is concerned with an improved method for the counter-current contacting of two immiscible or partially miscible liquids.

One object of my invention is to provide a process wherein one liquid may be passed over the surface of another liquid moving in the opposite direction, the two liquids being intimately contacted with each other and thereafter continuously and efficiently separated from each other.

Another object of my invention is to provide a suitable apparatus for carrying out this process.

Further objects of my invention will become apparent as the description thereof proceeds.

The nature of the invention will be made more apparent by reference to the accompanying drawing which illustrates one embodiment of it and in which:

Figure 1 is a longitudinal view partially in cross section and

Figure 2 is a vertical section taken along the line 2—2 of Figure 1.

In the drawing 11 refers to a substantially horizontal casing preferably of approximately U-shaped section having near the bottom of one end an inlet pipe 12 and near the top of the same end an outlet pipe 13. At the other end, the casing 11 is provided with an upper inlet pipe 14 and a lower outlet pipe 15 which may suitably be located at the bottom of a sump 16 formed by an extension of casing 11. The casing is equipped to carry a longitudinal shaft 17 extending throughout the whole or a portion of its length and carried by suitable bearings or journals 18 and 19. The shaft 17 is equipped to be rotated by suitable means, not shown, operating upon gear or pulley 20. The shaft 17 carries at various points in its length paddles 21. The casing 21 is partially divided into sections by baffles 22, which in a preferred form extend inwardly from the casing leaving a substantial opening around the shaft 17. Baffles 22 may suitably be provided with holes or valves, not shown, located near the point at which they join the lower portion of the casing, thereby making possible the complete removal of the contents of the apparatus thru pipe 15 if desired.

In the operation of this apparatus, two liquids are introduced and two liquids are withdrawn. The original liquid having the lower specific gravity is introduced through pipe 14, impinges against baffle 23 and flows through the apparatus, being removed by means of outlet pipe 13. The original liquid having the higher specific gravity is introduced through inlet 12, impinges

against baffle 24, flows through the apparatus and out through outlet pipe 15.

Although my process and apparatus will be found useful in a large number of cases in which it is desirable to contact two liquids continuously, it will be found to be of particular value in the selective extraction of lubricating oils by means of special solvents. It is known that when lubricating oil fractions are submitted to the solvent action of such materials as nitrobenzene, phenol, and dichlorethylether, the more naphthenic, and therefore less desirable, portions of the oil are dissolved, whereas the more paraffinic, and therefore more desirable, portions remain undissolved. In the past it has been usual to conduct such processes by raising the temperature of the solvent and oil until complete miscibility occurs and then lowering the temperature until a separation takes place. This process is time-consuming and requires large and expensive equipment. Furthermore, the extraction accomplished is less complete than when using my counter-current process. Another method of accomplishing these results has been to operate at a single temperature by merely agitating one or more batches of solvent and oil together and then allowing them to separate. This procedure is also time-consuming and requires unwieldy equipment. Furthermore, it does not accomplish as satisfactory a separation of the constituent fractions of the oil as does my method. This fact is quantitatively illustrated in a specific instance described hereinafter.

The process of my invention operates continuously and accomplishes better results than the former methods in less time and at less expense. Furthermore, my process can be accurately controlled. For instance, since the equipment is small it is relatively very easy to keep the temperature at the optimum point by lagging or jacketing the casing 11. Furthermore, the degree of agitation to which the two liquids are subjected can be delicately controlled by controlling the rate of rotation of shaft 17, for instance by means of a variable speed motor or variable reduction gears, not shown.

Furthermore, fresh incoming solvent will first come in contact with the oil which has been almost completely extracted, thus making the solvent having the greatest solvent power available for use on the oil most recalcitrant to solvent extraction, whereas at the other end of the apparatus the fresh incoming oil will come in contact with solvent which has taken up most of the undesirable constituents which it is capa-

ble of dissolving but the most readily extractable constituents will still dissolve in the nearly "spent" solvent. This makes certain the maximum possible utilization of the solvent power of the solvent and permits economies of time and material. In other words, by the use of my process and apparatus, the oil is extracted quickly, thoroly and efficiently to give the best possible fractionation into relatively paraffinic and relatively naphthenic constituents.

It will be understood that in the intermediate portion of my apparatus; that is, in the compartments formed by baffles 22 and containing the paddles 21, the two liquids will be agitated together in order to assure good contact and to bring about efficient extraction. However, the rate of rotation of shaft 17 must not be sufficiently high to produce thoro emulsification, since this would prevent the counter-current flow of the two liquids. The rate of rotation of shaft 17 will therefore be as high as is consistent with satisfactory operation. Any emulsion which may be formed in the intermediate portions of the apparatus will separate out in the end portions prior to withdrawal of the final liquids. In order to enhance this separation process, the casing 11 is preferably tilted at a slight angle from the horizontal, thereby causing the interface 25 of the two liquids to assume a slight angle to the axis 30 of the casing. This has the effect of providing a relatively deep layer of the heavy extracted liquid at the end where that liquid is being withdrawn and a relatively deep layer of the light liquid at the end where that liquid is being withdrawn. Since these two liquids are removed at points near the upper and lower ends of the casing respectively, there is thus obtained an increased hydrostatic head of the liquid being withdrawn at each end and this large head improves the efficiency of the separation of the emulsion under the influence of gravity.

As an example of my process:

Two hundred barrels of dichlorethylether may be gradually admitted to my apparatus thru pipe 45 12 while one hundred barrels of an acid-treated "mixed base" lubricating fraction having an S. A. E. number of 20 are being admitted thru pipe 14. The paddles 21 may be rotated at a moderate speed and the dichlorethylether together with extracted oil may be withdrawn thru pipe 15 while the residual oil together with some dissolved dichlorethylether is withdrawn thru pipe 13. The solvent may be removed from each of these two products by distillation. On examination it will be found that the original oil has been fractionated into two very different materials having the following properties as compared with the original oil:

temperature with the same amount of dichlorethylether, allowed to settle and the solvent removed, the properties of the residual oil would compare as follows with the properties of the residual oil produced by my process:

	My process	Simple extraction	10
Viscosity at 100° F.....	228	265	
Viscosity at 210° F.....	48	48	
Resistance to sludging.....	Excellent	Fair.	

Although my invention has been described in conjunction with a specific embodiment thereof, it is to be recognized that many modifications can be made without departing from the spirit thereof. For instance, casing 11 may be of any desired form and may be provided with other types of baffle equipment to suit the exigencies of the 20 particular case.

As an example of another possible modification it is to be understood that outlet pipe 13 could conveniently be replaced by a weir. It will furthermore be readily comprehended that in the event serious emulsification difficulties are encountered the end sections of the apparatus may be suitably enlarged or extended. Under other circumstances it may be desirable to elongate the central portion of the apparatus in order to 30 achieve more thoro contacting and greater utilization of the counter-current features of the process.

Baffles 22 may be of other forms. The form shown is highly suitable in many cases, since the liquids passing from one section to the next must pass near the shaft at intervals, thereby assuring that only the most thoroly contacted portions are passed on to the next compartment. Other forms of baffle including perforated plates, 40 may be suitably used, in some cases. Additional baffles may be added.

Altho the present invention has been described in connection with the details of a specific embodiment thereof, it is not intended that such details shall be regarded as limitations upon the scope of the invention, except insofar as included in the accompanying claims.

I claim:

1. A process for the solvent extraction of lubricating oils in a series of zones arranged in an approximately horizontal lineal relationship to each other and comprising two end zones and a plurality of intermediate zones, said process comprising admitting a stream of lubricating oil at a point near the end of one of said end zones, flowing said stream thru all of said zones in succession, admitting a stream of solvent near the end of the

60	Original oil	Residual oil	Extracted oil	60
Yield.....	100%	70%		
Nature.....	Mixed base	Relatively paraffinic		
Viscosity at 100° F.....	306 sec. Saybolt	228 sec. Saybolt		
Viscosity at 210° F.....	50 sec. Saybolt	48 sec. Saybolt		
65 Resistance to sludging.....	Poor	Excellent	30% Relatively naphthenic. Highly viscous and sticky. Not suitable as lubricating oil.	65

It will thus be seen that by the use of my process a poor lubricating oil may be made to 70 yield 70% of an excellent lubricating oil, resistant to sludging and having a very low temperature coefficient of viscosity. This process is much more efficient than simple agitation and settling. To illustrate this: if the same amount of this 75 same original oil is thoroly agitated at the same

end zone opposite said last-mentioned end zone, flowing said stream of solvent thru all of said zones in succession in a direction opposed to the direction of flow of said stream of lubricating oil, and in continuous contact therewith, continuously partially commingling said stream of solvent and said stream of lubricating oil throughout said intermediate zones as thoroly as possible with- 75

- out producing substantial permanent emulsification, separating said partially commingled streams in each of said end zones and separately removing the two resultant liquids from opposite 5 end zones.
2. A process for the solvent extraction of a mixed base lubricating oil fraction with a solvent comprising dichlorethylether, said process comprising flowing a stream of said solvent thru a 10 plurality of contact zones, flowing a stream of said lubricating oil through said plurality of contact zones in a direction opposed to the direction of flow of said stream of solvent, partially commingling said stream of solvent and said stream 15 of lubricating oil in the contact zones intermediate of the end contact zones and separately withdrawing from opposite end contact zones, a resultant liquid comprising the major portion of said solvent containing in solution a minor portion 20 of said lubricating oil, said minor portion comprising the relatively naphthenic constituents of said lubricating oil, and removing from the end zone opposite said last-mentioned end zone a resultant liquid comprising a minor portion of said 25 solvent and a major portion of said lubricating oil, said major portion comprising the relatively paraffinic constituents of said lubricating oil.
3. A process for contacting a liquid with a second liquid partially miscible with said first-mentioned liquid in a series of zones arranged in an 30 approximately horizontal lineal relationship to each other and comprising two relatively quiescent end zones and a plurality of intermediate zones, said process comprising admitting a stream 35 of said first-mentioned liquid into one of said end zones, flowing said stream through all of said zones, in succession, admitting a stream of said second liquid into the end zone opposite said last-mentioned end zone, flowing said stream of said 40 second liquid through all of said zones in succession in a direction opposed to the direction of flow of said stream of said first-mentioned liquid and in continuous contact therewith, continuously partially commingling said stream of said first 45 mentioned liquid and said stream of said second liquid in said intermediate zones as thoroughly as possible without producing substantial permanent emulsification, separating said partially commingled streams in each of said end zones and 50 separately removing the two resultant liquids from opposite end zones.
4. In a process for the continuous counter-current contacting of a lubricating oil stock and a solvent selected from the class comprising nitro- 55 benzene, phenol and dichlorethylether in a series of partially segregated contact zones, the steps which comprise coagitating said stock and said solvent in each of said contact zones intermediate the end contact zones but not in said end 60 contact zones and restraining the passage of the less thoroughly contacted portions of said stock and said solvent from each of said contact zones to the next adjacent contact zone while permitting the more thoroughly contacted portions of 65 said stock and said solvent in each of said contact zones to pass to the next successive contact zone.
5. A process for the continuous countercurrent 70 contacting of two liquids in a series of zones arranged in an approximately horizontal lineal relationship to each other and comprising two end zones and a plurality of intermediate zones, said process comprising admitting a stream of one of said liquids into one of said end zones, flowing 75 said stream through all of said zones in succession, admitting a stream of the other of said liquids into the end zone opposite said last-mentioned end zone, flowing said stream of said first-mentioned liquid through all of said zones in succession in a direction opposed to the direction of flow of said stream of said second-mentioned liquid and in continuous uninterrupted contact therewith, continuously partially commingling said two streams throughout said intermediate zones as thoroly as possible without producing such thoroy emulsification as to interfere with countercurrent flow, separating said partially commingled streams in each of said end zones and separately removing the two resultant liquids from opposite end zones restraining the passage of all but the most thoroly commingled portions of said two streams from passing from zone to zone.
6. A process according to claim 5 in which said two liquids are an oil and a selective solvent. 20
7. A process according to claim 5 in which said two liquids are a lubricating oil stock and a selective solvent for the relatively naphthenic portions of said stock.
8. A process according to claim 5 in which said two liquids are a lubricating oil stock and dichlorethylether. 25
9. A process for the continuous counter-current treatment of a lubricating oil stock comprising relatively paraffinic constituents and relatively naphthenic constituents in a series of contact 30 zones arranged in substantially horizontal linear relationship to each other and comprising two end contact zones and a plurality of intermediate contact zones, said process comprising admitting a stream of said lubricating oil stock to one of said end contact zones, flowing said lubricating oil stock through all of said contact zones in succession, admitting a selective solvent for said relatively naphthenic constituents to the end contact 35 zone opposite said first mentioned end contact zone, flowing said selective solvent through all of said contact zones in succession in a direction opposed to the direction of flow of said lubricating oil stock and in continuous contact with said lubricating oil stock, continuously partially commingling said selective solvent and said lubricating oil stock throughout at least some of said intermediate contact zones substantially as thoroly as possible without producing substantial 40 emulsification in the topmost and bottom-most strata, and separately removing the two resultant liquids from opposite end contact zones. 45
10. A process for the continuous counter-current treatment of a mineral lubricating oil stock comprising relatively paraffinic and relatively naphthenic constituents with a selective solvent comprising dichlorethylether, said process comprising flowing a stream of said selective solvent through a series of contact zones comprising two 50 end contact zones and a plurality of intermediate contact zones, flowing a stream of said lubricating oil stock through the same series of contact zones in a direction opposed to the direction of flow of said stream of said selective solvent, partially commingling said two streams in said intermediate contact zones, and separately withdrawing from opposite end contact zones two resultant liquid phases comprises respectively the bulk of said 55 selective solvent together with said relatively naphthenic constituents and the remainder of said selective solvent together with said relatively paraffinic constituents.

CERTIFICATE OF CORRECTION.

Patent No. 2,029,687,

February 4, 1936

ROBERT E. WILSON.

It is hereby certified that error appears in the printed specification of the above numbered patent requiring correction as follows: Page 3, first column, strike out lines 28 to 51 inclusive, comprising claim 3; same page, second column, line 12, claim 5, before the word "separating" insert the words and comma restraining the passage of all but the most thoroly commingled portions of said two streams from passing from zone to zone,; and in line 15, same claim, beginning with the word "restraining" strike out all to and including the word "zone", line 18; same page and column, line 69, claim 10, for "comprises" read comprising.

The claims now appearing in the patent as numbers 4, 5, 6, 7, 8, 9 and 10 should bear the numbers 3, 4, 5, 6, 7, 8 and 9 respectively; and that the said Letters Patent should be read with these corrections therein that the same may conform to the record of the case in the Patent Office.

Signed and sealed this 7th day of April, A. D. 1936.
